UNITED STATES PATENT OFFICE.

GEORGE B. ELY, OF ELKHART, INDIANA, ASSIGNOR TO WESTINGHOUSE ELECTRIC & MANUFACTURING COMPANY, A CORPORATION OF PENNSYLVANIA.

SECTION-INSULATOR.

1,249,359.

Specification of Letters Patent. Patented Dec. 11, 1917.

Application filed March 13, 1916. Serial No. 83,750.

To all whom it may concern:

Be it known that I, GEORGE B. ELY, a citizen of the United States, and a resident of Elkhart, in the county of Elkhart and State 5 of Indiana, have invented a new and useful Improvement in Section-Insulators, of which the following is a specification.

My invention relates to overhead construction for electric trolley lines and it has special relation to section insulators for use in connection with trolley lines that are operated under high voltages and in connection with high-speed sliding or pantograph trolleys.

15 The object of my invention is to improve the construction of section insulators of the above indicated character and, in particular, to provide such an insulator in which the insulating member may be readily replaced 20 without changing any of the connections to the adjacent trolley sections or glider attachments.

In the accompanying drawing, Figure 1 is a side elevational view of a section insulator constructed in accordance with my invention, and Fig. 2 is a plan view of the apparatus shown in Fig. 1.

A section insulator of the type to which my present invention relates consists essentially of a strip of wood or other insulating material provided with connecting means at its opposite ends for attachment to adjacent trolley conductor sections. It is also usual to provide arms or gliders that extend obliquely outward from opposite sides of the insulator, these gliders being designed to afford a continuous conducting path for the pantograph as it traverses the insulator. It has heretofore been customary to attach such 30 gliders, and also the ends of the adjacent trolley conductor sections, directly to castings secured to the ends of the insulating strip. When an insulator constructed in this manner is in need of repairs or replacement, considerable time and labor are required to disconnect the insulator from the trolley sections and to make the necessary attachments to restore the insulator to its operative condition.

50 According to my present invention, the trolley conductors and gliders are not directly attached to the insulating member, but are secured to connecting members that releasably engage the end castings of the insulator by means of hooks or otherwise,

The insulator shown in the accompanying drawing consists of an insulating strip 1, of wood or other non-conducting material, to which are bolted end castings 2 and 3, each of these castings being provided with two outwardly extending ears 4 which are perforated to receive a transverse bolt 5.

Coöperating with each of the end castings just described is a connecting member 6 provided with a hook 7 which engages the bolt 5 and, when the device is under tension, serves to hold the insulator in place. The member 6 is forked and is perforated to receive transverse bolts 8, 9 and 10. The bolts 8 and 9 are adapted to receive connectors 11 and 12, respectively, by means of which connection is made to the adjacent sections of the trolley conductor and the feeder conductor. Each of the transverse bolts 10 loosely supports a guide 13, of inverted V-shape, the lower ends of which are attached to a glider 14 which may be of any usual or desired construction to extend outwardly, as shown in Fig. 2. The weight of the glider 14 is supported by means of a 75 spring 15 the ends of which are attached at 16 to the hooked connecting member 6, the connection between the glider 14 and the spring 15 being adjustably effected by means of a rod 17 and clamps 18 and 19.

The shape of the guide 13 is so selected that free movement is permitted between the guide and the bolt 10, so that the glider 14 is permitted to move freely against the pressure of the trolley, and the formation of 80 hard spots at these points is thereby avoided. The bolts 9, as shown in Fig. 2, are provided with eye nuts 20 to which the usual steady spans may be attached.

In its normal operation, my device does 95 not differ materially from the section insulators which have heretofore been in use. When, however, replacement or repairs are required, it is only necessary to remove the strain of the trolley from the insulator, by 100 means of a set of blocks or otherwise, when the insulating section can be disengaged from the hooks 7 and replaced without disturbing either the trolley connections or the glider attachments. A considerable saving 105 in time and labor is thereby effected.

The structural details which I have shown and described are those which I have found to be advantageous for the purposes indicated, but it is to be understood that numer- 110

ous modifications may be made without departing from the scope of my invention. It is therefore to be understood that no limitations are to be imposed upon my invention 5 except such as are indicated in the appended claims.

I claim as my invention:

1. A section insulator for trolley conductors comprising an insulating member, 10 and means for connecting the opposite ends of said member to the trolley-conductor sections, said insulating member being so constructed that it is freely removable from the structure by drawing the connecting 15 means toward one another and lifting said member vertically from the structure.

2. A section insulator for trolley conductors comprising an insulating member and a connecting member releasably attached 20 to one end of said insulating member, said members being so constructed that drawing said members together renders said insulating member freely removable.

3. A section insulator for trolley conductors comprising an insulating member and a connecting member provided with a hook for attachment to the said insulating member, said members being so constructed that drawing said members together causes 30 said hook to become disengaged from said insulating member and renders said insulating member freely removable.

4. A section insulator for trolley conductors comprising an insulating member, 35 a connecting member releasably attached to one end of the said insulating member, and a glider supported by said connecting member.

5. A section insulator for trolley con-

ductors comprising an insulating member, a 40 connecting member provided with a hook for attachment to the said insulating member and also provided with means for attachment to an adjacent trolley-conductor section, and a glider supported by the said con- 45 necting means.

6. A section insulator for trolley conductors comprising an insulating member, castings secured to the opposite ends of the 50 said insulating member and provided with transverse bars forming open eyes, and connecting members carrying gliders and provided with hooks for engaging the said transverse bars and also provided with means for attachment to adjacent trolley- 55 conductor sections.

7. A section insulator for trolley conductors comprising an insulating member, castings secured to the opposite ends of said 60 insulating member, connecting means releasably attached to said castings and adapted to be secured to an adjacent trolley-conductor section, and a glider supported by said connecting means and independent of said insulating member. 65

8. A section insulator comprising an insulating member provided with end castings, a glider, and a connecting member interposed between a trolley-conductor section and one of said castings and releasably 70 engaging one of said castings, said glider being resiliently supported by said connecting member.

In testimony whereof, I have hereunto 75 subscribed my name this 9th day of Mar., 1916.

GEO. B. ELY.
